O. SCHUBERT

JOINT OR COUPLING FOR POSTS

Filed Jan. 13, 1925

FIG.1.

FIG.3.

FIG. 2.

FIG. 4.

Inventor.

Oskar Schubert.

Attorney. R. Mauday

UNITED STATES PATENT OFFICE.

OSKAR SCHUBERT, OF FREIBURG, GERMANY, ASSIGNOR TO GEBR. HIMMELSBACH AKTIENGESELLSCHAFT, OF FREIBURG, GERMANY.

JOINT OR COUPLING FOR POSTS.

Application filed January 13, 1925. Serial No. 2,240.

To all whom it may concern:

Be it known that I, OSKAR SCHUBERT, residing at Freiburg, Baden, Germany, a citizen of the German Republic, have invented 5 certain new and useful Improvements in Joints or Couplings for Posts, of which the following is a specification.

The object of my invention is to provide improved means for connecting poles or 10 lengths of timber for making composite posts. For this purpose substantial strength and rigidity are required, and it has been proposed to use corrugated metal coupling plates, screwed to the timber, and 15 in some cases plates which are intended to touch the timber only at their edges, so that there is a cavity between the metal and the timber. This cavity is in some respects useful, and I aim at retaining the same, with 20 my invention, but heretofore it has been found that by screwing up the plate the same is distorted and bent, so that more or less close contact occurs, where the cavity was desired.

According to my invention a curved metal 25 plate is folded along two parallel edges which are parallel with the axis of curvature, the parts folded over forming beads, at the bends, and then lying in part against the inside or concave face of the plate, their 30 inner edges, however, being bent away from the face of the plate to form flanges, whose depth is substantially equal to the depth of the beads. The radius of the plate 35 curvature is somewhat larger than the radius of the post. I make holes for screws in the double thickness of the plate, where it has been folded.

The plate being placed against the post, 40 touches the same only with the beads and the flanges, if the portion between the flanges is left in the form of a segment of a cylinder, but I may bend this part inwards, to form a channel or channels, so that a portion or portions thereof will abut against the post.

The screw inserted through the holes in 50 the double thickness of metal between the beads and flanges can be screwed in very tightly without substantially distorting the plate, because the beads and the flanges form strong and rigid abutments for taking the

thrust. There is practically no risk of so distorting any part of the plate that it will make contact with the post, except with the 55 beads and the edges of the flanges, and with such other part as may have previously been bent inwards for the purpose of making contact.

Two constructions according to the invention are shown in the accompanying drawing, in Figs. 1 and 2 and in Figs. 3 and 4 respectively.

Fig. 1 is an elevation of a coupling plate, partly broken away, looking towards the 65 concave face thereof, and

Fig. 2 is a cross section of this plate, applied to a post.

Figs. 3 and 4 are similar views of the second construction. 70

Referring first to Figs. 1 and 2, *a* is the cylindrically curved part of the plate, *b*, *b* are the beads, *c*, *c* the flanges, and *d*, *d* holes for the insertion of screws, as shown at *e* in Fig. 2, *f* being the post. 75

In the construction shown in Figs. 3 and 4 the folding at the lateral edges is precisely similar to that shown in Figs. 1 and 2, but the part *h* between the flanges has two sharp inward bends, as at *h*, to form a channelled part *g*, which abuts against the post *i*. I may provide holes for screws in the part *g*.

What I claim as my invention and desire to secure by Letters Patent of the United States is:—

1. A metal coupling plate for the purpose set forth, curved and folded along two parallel edges parallel with the axis of curvature, the folded portions forming beads 90 at the bends and lying in part against the concave face of the plate, and the inner edges of said folded parts being bent away from said concave face to form flanges.

2. A plate as claimed in claim 1, having 95 holes for screws in the double thickness of metal formed by the folding thereof.

3. A plate as claimed in claim 1, having a portion thereof bent to form a ridge between 100 the flanges.

In witness whereof I have signed this specification.

OSKAR SCHUBERT.
